DESIGN FOR A PRINT MOUNTER

Frank Kuhn, Grosse Pointe Farms, and Laurence H. Thomas, Birmingham, Mich., assignors to American Electrical Heater Company, Detroit, Mich., a corporation of Michigan

Application May 8, 1939, Serial No. 84,878

Term of patent 14 years

To all whom it may concern:

Be it known that we, Frank Kuhn and Laurence H. Thomas, citizens of the United States of America, residing at Grosse Pointe Farms and Birmingham, respectively, in the counties of Wayne and Oakland, respectively, in the State of Michigan, have invented a new, original, and ornamental Design for a Print Mounter, of which the following is a specification, reference being had therein to the accompanying drawing, forming a part thereof, wherein the figure is a perspective view of a print mounter, showing our new design.

The essential feature of the design is the rectangular base portion with sharp angle corners and the superposed portion starting from a sharp angle and gradually merging into a rounded surface from the bottom upward together with rounded corners between the several sides and the top.

We claim:

The ornamental design for a print mounter, substantially as shown and described.

FRANK KUHN.
